Primary Examiner — Erich G Herbermann*Assistant Examiner* — Andrew D Golson(74) *Attorney, Agent, or Firm* — Grants Law Firm; Allan Grant(57) **CLAIM**

The ornamental design for a gate, as shown and described.

DESCRIPTION

FIG. 1 is a rear, side, top perspective view of a gate, showing my new design;

FIG. 2 is the front view of the gate of FIG. 1;

FIG. 3 is a back view of the gate of FIG. 1;

FIG. 4 is a side view of the gate of FIG. 1;

FIG. 5 is the other side view of the gate of FIG. 1;

FIG. 6 is a top view of the gate of FIG. 1; and,

FIG. 7 is bottom view of the gate of FIG. 1.

The broken lines in the drawings depicting the gate handle, lock, and gate wood inserts are portions of the gate that form no part of the claimed design.
